Primary Examiner—Nelson C. Holtje**Assistant Examiner—Jeffrey Asch****[57] CLAIM****The ornamental design for a sidekick display device, as shown and described.****DESCRIPTION**

FIG. 1 is a perspective view as seen from the top, front and left side of a sidekick display device;
 FIG. 2 is a front elevational view;
 FIG. 3 is a right side elevational view, the left side elevation being a mirror image;
 FIG. 4 is a top plan view;
 FIG. 5 is a bottom plan view;
 FIG. 6 is a rear elevational view; and,
 FIG. 7 is a perspective view of a sidekick display device, the broken linework is for environmental purposes only and does not constitute a part of our new design.

FIG. 1

FIG. 2

FIG. 3

FIG. 4

FIG. 6

FIG. 5
